IMPREGNATING APPARATUS

Walter P. Abell, Quincy, Mass., assignor to United
Shoe Machinery Corporation, Flemington, N. J.,
a corporation of New Jersey

Application September 14, 1942, Serial No. 458,277

22 Claims. (Cl. 91—46)

The purpose of the present invention is to provide improvements in impregnating apparatus of the type in which power-operated mechanism is used to immerse the work in a liquid impregnant and to remove the work therefrom.

One of the features provided by the invention consists in means for regulating the depth of immersion of articles of work that require immersion of one portion but not of another. An example of this requirement is that of wetting or waterproofing the foreparts and shanks of unattached leather soles without immersing the heel seats thereof. To this end the improvement under consideration includes a holder or container for supporting the work, power-operated mechanism for carrying the holder down and up, and adjustable means for arresting the downward travel of the holder at any one of various levels without disturbing the carrying mechanism or modifying its range of action.

The invention also provides means for automatically replenishing the liquid impregnant to a predetermined initial level to counteract the quantities absorbed by the work. This replenishing means is capable of being regulated to vary the initial level above mentioned, and such regulation may also be used to vary the depth of immersion.

Still another improvement consists in a novel combination including the aforesaid power-operated mechanism, means for automatically interrupting the operation thereof, and timing means for restarting such operation at the conclusion of one or more measured intervals of dwell. This combination provides for giving the work one or more measured periods of dwell in the liquid impregnant with or without one or more measured periods of dwell out of the impregnant. For tempering leather soles with water it is desirable to leave them in the water long enough to load their surfaces with water but not so long as to render their surfaces sodden, then to remove them from the water for a period long enough to enable capillary action to carry the water from their surfaces into the interior of the leather, and in some circumstances to repeat such treatment as many times as may be necessary to condition the soles for the usual series of bottoming operations on welt shoes and McKays as practiced in shoe factories.

The features above mentioned and others hereinafter described are organized in the illustrated embodiment of the invention to lower and raise the articles of work within the confines of a

treatment chamber in the upper portion of which warm water-vapor may be used to supplement the treatment effected by immersing the soles in water in the lower portion of the chamber. In this respect the apparatus may be used to practice the method disclosed by W. E. Phinney in Letters Patent of the United States, No. 2,348,413, granted May 9, 1944.

Referring to the drawings, 10 Fig. 1 is a vertical section of an impregnating apparatus embodying the invention in a form designed for tempering unattached leather soles;

Fig. 2 is a horizontal section on a larger scale of the structure within the range of line II—II in Fig. 1;

Fig. 3 is a vertical section of the apparatus in a plane at right angles to that of Fig. 1. The plane of Fig. 3 is front to rear, while that of Fig.

20 1 is side to side;

Fig. 4 is a vertical section on a larger scale of an operating connection otherwise represented in Fig. 3;

Fig. 5 is a top plan view of a mechanism for 25 carrying the work into and out of a liquid impregnant and includes means for producing intermittent operation thereof;

Fig. 6 is a front elevation projected from Fig. 5, of timing means for interrupting and restarting 30 the work-carrying mechanism;

Fig. 7 is a vertical section on a larger scale of the structure within the range of line VII—VII in Fig. 6;

Fig. 8 is a vertical section of a valve mechanism 35 intersected by line VIII—VIII in Fig. 7;

Fig. 9 is a sectional view of a relief valve in the plane indicated by the line IX—IX in Fig. 7;

Fig. 10 is an elevation of an assemblage comprising two mercury switches for controlling electrical circuits;

Fig. 11 is an elevation of an individual mercury switch that operates in series with one of the switches represented in Fig. 10;

Fig. 12 is a vertical section of a portion of a timing unit for closing the switch represented in Fig. 11;

Fig. 13 is a wiring diagram including three electrical circuits;

Fig. 14 represents a flat development of a pneumatic equipment including a timing unit and means for supplying air above atmospheric pressure;

Fig. 15 is a vertical section of a supplemental tank included in Fig. 3 and provided for the pur-

pose of replenishing the impregnating chamber with liquid impregnant;

Fig. 16 is an elevation of a counting unit by which all operation of the apparatus is stopped at the conclusion of a predetermined number of work-carrying cycles; and

Fig. 17 is a sectional view in the plane indicated by line XVII—XVII in Fig. 5.

Referring to Figs. 1 and 3, a metallic tank 20 and a domed cover 21 form a closed impregnating chamber 22 for holding a body of liquid impregnant 23. The tank is superposed upon a hollow base 19 that encloses a mechanism for moving the work up and down in the tank. The cover 21 is connected to the tank 20 by hinges such as that indicated at 24 and the hinges are provided with cooperative stop portions 25, 26 arranged to maintain the cover in an upright position when it is opened as far as it will go.

For purposes of description but not of limitation, it will be assumed that the apparatus is to be used for impregnating unattached leather soles with water in accordance with the usual requirements of shoe-bottoming operations in shoe factories. Proceeding on this basis, the tank 20 is of a size to accommodate a cage 27 for containing a suitable number of cases of soles 28 loosely tied with cords 29 to maintain them in stacked relation. To provide for immersing the foreparts and the shanks of the soles in the water 23 without immersing the heel seat portions, the soles will be stood on their toe ends as shown in Fig. 3.

To guide the cage 27 in the desired path, each of the two side walls of the tank 20 is provided with a pair of vertical guiding strips 30 of L-section (see Fig. 2). These strips may be welded to the tank or secured thereto by rivets. The strips of each pair are spaced one from the other to form a guiding channel. Two blocks or shoes 31 are affixed to the cage at diametrically opposite points near the top thereof (Fig. 1) to run in the guiding channels, and two pairs of blocks or shoes 32 are affixed to the cage near the bottom, but these are arranged to run on the outer surfaces of the strips 30 (Figs. 2 and 3) instead of running in the channel between the strips. Each channel is occupied by a vertically adjustable strip 33 having an inwardly projecting block 34 at its lower end and an outwardly projecting block 35 at its upper end. The blocks 35 project through vertical slots 36 in the tank, each flanked by a pair of strips 37 welded to the outer surface of the tank. The blocks 34 constitute stops for the shoes 31, but the blocks 35 serve as handles by which the blocks 34 may be adjusted up and down to arrest the descent of the cage at various levels. Each strip 37 is provided with a series of holes 38 to receive a pin 39 (Fig. 2) which may be inserted in any desired pair of holes. When the blocks 35 are located above the pins they will be supported by the latter. The stops 34 will be adjusted with due regard to the length of the soles to be impregnated and with regard also to the level of the water and the depth of immersion desired.

The bottom of the cage comprises a series of slats 41 and a work-supporting grid 40 of coarse wire fabric resting on them. The slats are preferably arranged to prevent spattering the soles with liquid when the cage is elevated, but at the same time, they will permit vapor to rise through the bottom of the cage and to circulate freely between and around the soles.

To provide for heating the liquid the tank 20

is provided with a series of electric heating units 42 (Fig. 3) encased in metal tubes 43 and arranged to be immersed in the liquid as shown in Fig. 1. The open end of each tube 43 is fastened to a wall of the tank to form a water-tight joint. This wall is provided with openings (not shown) to receive electrical conductors by which current will be supplied to the heating units. The units are connected in parallel in a circuit 44 that also includes a thermal regulator or switch 45 (Fig. 13). The thermal element 46 of this regulator is arranged to be immersed in the water 23 (Figs. 1 and 3). This type of regulator is obtainable in the open market and is usually provided with a manually adjustable member 47 (Fig. 1) for varying the maximum temperature of the liquid.

Figs. 3 and 15 illustrate means for automatically replenishing the liquid in the tank 20 as quantities thereof are used in the treatment of the work. For this purpose a replenishing tank 50 is affixed to the rear wall of the tank 20. A pipe 51 provides communication between the tanks by which the liquid in both is maintained in equilibrium. Water under a suitable head is supplied to the tank 50 by a pipe 52 provided with a manually operable shutoff valve 53. The discharge of water into the tank 50 is automatically controlled by a ball cock 54 operated by a float 55. The lever 56 operated by the float is provided with a thumb screw 57 for closing the ball cock and for regulating the level at which it will be closed.

A mechanism for periodically immersing the soles in the water 23 is illustrated in Figs. 1, 3 and 5. It comprises an assemblage of gearing mounted in an open frame structure 58 of generally rectangular form in which bearings are provided for two crank shafts 59, 59, two countershafts 60, 60 and a driving shaft 61. The adjacent ends of the shafts 59 are spaced one from the other and provided with spur gears 62, 62 that carry flat steel rings 63, 63. These rings are also spaced one from the other to provide a clear, unobstructed path for vertical movement of a horizontal crosshead 64. This head is affixed to the lower end of a plunger 65 that extends through a stuffing box 66 formed on the bottom of the tank 20. The head 64 bears on the upper sides of two cooperative antifriction rolls 67, 67 (Fig. 4) carried respectively by the rings 63. The rings and rolls constitute a crank, although the rolls are arranged to travel in individual paths to enable them to clear each other when the ring 63 are rotated in opposite directions. A strap 68 of steel is affixed to the ends of the head 64 (Fig. 1) and arranged to be engaged by the undersides of the cranks to insure downward movement of the plunger 65 despite the friction due to compression of the packing in the stuffing box 66.

The cranks 63, 67 are located and driven to operate in synchronism with each other but they are driven in opposite directions at equal speeds. This duplex construction of the crank balances the forces applied to the head 64 at all stages and relieves the plunger 65 from bending strains that would be unavoidable if only one roll were used.

As shown in Fig. 5, the gears 62 are driven by individual pinions 69 carried by the countershafts 60. Each of these countershafts is provided with a worm wheel 70 (see also Fig. 17) one engaging a right-hand worm 71 and the other engaging a left-hand worm 72. The worms are carried by the driving shaft 61 on which a pulley 73 is secured to receive rotation from a

V-belt 74 (Fig. 3). This belt is driven by an electric motor 75 provided with a driving pulley 76.

The upper end of the plunger 65 carries a spider 77 that provides a platform for supporting the cage 27. The spider may be affixed to the plunger 65 or to the cage 27 but not to both, because the stops 34 may be adjusted to arrest the downward travel of the cage before the plunger has reached the lower limit of its range of travel.

Referring to Fig. 13, the motor 75 is included in an electrical circuit 78 that also includes a mercury switch 79 and a mercury switch 80 arranged in series. To characterize these switches by their functions, the switch 79 may be considered the primary or starting switch, and the switch 80 may be considered the interrupting switch by which the operation of the work-carrying means is to be periodically interrupted during a process of impregnation. In Figs. 10 and 13 the primary switch 79 is represented in the closed position while the interrupting switch 80 is represented in the open position in Figs. 3, 11 and 13. These are the positions they occupy when the operation of the work-carrying mechanism is temporarily interrupted at an intermediate stage in a process of treatment. The primary switch 79 is closed manually and opened by automatic means, but the interrupting switch 80 is opened and closed only by automatic means.

The interrupting switch 80 is also represented in Fig. 3. It is clamped in a holder 81 affixed to a rockshaft 82 that has a range of angular movement indicated by a double-headed arrow in Fig. 12. An arm 83 secured to the rockshaft carries a trip latch 84 connected thereto by a pivot 85. The force of gravity of the parts carried by the rockshaft 82 is sufficient to rock the switch 80 to the closed position when the latch 84 is released from restraint, but Figs. 11 and 12 show how the switch is held in the open position by cooperation of a shoulder 86 of the latch and a pin 87 carried by another arm 88. This arm is one element of a power-operated mechanism by which the switch 80 is tilted from the closed position to the open position. The arm 88 is affixed to a rockshaft 89 which also carries a finger 90. This finger is actuated twice in every work-carrying cycle to interrupt the operation of the motor 75, once when the plunger 65 is at or near its lowest position and once when it is at or near its highest position.

For the purpose last mentioned, the frame 58 (Figs. 1 and 7) is provided with bearings for a vertically movable bar 91 that receives short downstrokes and upstrokes alternately from the head 64. The bar is normally supported midway between its limits of travel by an arm 93 affixed thereto and a compression spring 92 surrounding the bar and seated on the lower bearing in which the bar slides. The spring enables the bar to be depressed below and raised above its median position. In Fig. 7 the median position of the arm 93 is indicated by dotted lines and the corresponding position of the lower end of the bar 91 is also indicated by dotted lines. The strokes of the bar are utilized not only to open the switch 80 but also to control a timing apparatus by which the switch is closed to restart the motor 75.

Again referring to Fig. 1, an arm 94 affixed to the upper end of the bar 91 is provided with a screw 95 to be engaged and raised by the head 64. The arm 94 has sliding engagement with a stationary pin 96, the purpose of which is to prevent turning movement of the bar 91 about its own axis. For the purpose of depressing the bar

91 below its median position, the lower end of the bar is provided with an arm 97 arranged to be engaged by the strap 68 affixed to the head 64.

Referring to Fig. 7, the upper portion of the bar 91 is provided with two oppositely inclined camming surfaces 98 and 99, each arranged to displace a follower 100 to the left against the force of a tension spring 101 (Fig. 12) that normally pulls down the arm 88 and thereby presses the finger 90 against a fin 102 carried by the follower. The follower slides in a bore in the bearing member 103 in which a kerf 104 is formed to receive the fin 102. The fin constitutes a spline by which the follower is prevented from turning about its axis. The junction of the cam surfaces 98 and 99 is located to coincide with the axis of the follower 100 when the bar 91 is in its median position. Consequently, whenever the work-carrying mechanism permits the bar to return to its median position the arm 88 (Fig. 12) will be drawn down by the spring 101 but the next stroke of the bar in either direction will raise the arm 88 to the position represented in this figure, thereby rocking the interrupting switch 80 to its open position.

The intervals of interruption in the operation of the motor 75 are measured by pneumatic timing means under control of the vertically movable bar 91. For this purpose a piston 105 (Fig. 12) is arranged to travel up and down in a pneumatic cylinder 106, the upper end of which is located adjacent to the trip latch 84 and is provided with a central vent 129. When the piston is at the upper limit of its travel, a pin 107 carried thereby projects through the vent to engage and actuate a rocker 108 mounted on the cylinder head and connected thereto by a pivot 109. This rocker is weighted to stand normally in the position shown in Fig. 12 but when it is actuated by the pin 107 it displaces the trip latch 84 with a movement sufficient to disengage the shoulder 86 from the pin 87. When this occurs, the switch 80 is tilted to its closed position by the weight of the elements carried by the rockshaft 82, with the result that the motor 75 is restarted. Almost immediately the bar 91 (Fig. 7) returns to its median position, thereby permitting the spring 101 (Fig. 12) to pull down the arm 88. The pin 87 is thus carried to a level below the shoulder 86 of the trip latch, whereupon the force of gravity tilts the latch to place the shoulder in the path of the pin. The next upward movement of the pin returns the trip latch to the position shown in Fig. 12, the camming surfaces 98 and 99 (Fig. 7) being effective alternately to produce this result.

The piston 105 starts to descend at the moment when the arm 88 is pulled down by the spring 101. Consequently, the trip latch has ample time in which to swing over the pin 87 before the next upward movement of the arm 88.

Referring to Fig. 3, air above atmospheric pressure is supplied by a centrifugal pump 110 that receives rotation from an electric motor 111 to which it is connected by a belt 112 that runs on a driving pulley 113 and a driven pulley 114. A pipe 115 connected to the output side of the pump conducts air to a duct 116 (Fig. 8) in a valve casing 117. This valve casing is affixed to the frame 58 adjacent to the vertically movable bar 91. Two horizontal ducts 118 and 119 receive air from the duct 116 and they deliver the air to two individually adjustable needle valves 120 and 121, but at points between the supply duct 116 and the needle valves the flow of air through the ducts

118 and 119 is controlled by individually movable slide valves 122 and 123. These valves are normally closed by springs 124 but they are both closed at the same time only when the bar 91 stands in its median position. The valves 122 and 123 are aligned with each other and when both are closed the gap between their adjacent ends is just equal to the thickness of a portion of the arm 93 that projects between them. In Fig. 8 the arm 93 is at the upper limit of its range of travel, and the valve 122 is thereby shifted to its open position to permit air to flow to the needle valve 120. Under these conditions the valve 123 is closed to prevent air from flowing to the needle valve 121. On the other hand, when the arm 93 is depressed to its lowest position, represented by dotted lines in Fig. 8, it will open the valve 123 while the valve 122 remains closed.

The needle valves 120 and 121 regulate the quantity of air that may flow through branches 125 and 126 of a common feed pipe connected to the lower end of the pneumatic cylinder 106. A diagrammatic representation of these pneumatic elements is provided in Fig. 14.

The piston 105 has a close but easy running fit in the cylinder 106 to enable the force of gravity to return it to the lower end of the cylinder whenever the column of air below it is released. Since the air supply is conducted alternately through two branches, each having an individual needle valve, the latter may be adjusted to produce unequal rates of upward travel of the piston 105. For this purpose the needle valves are provided with handles 127 and 128. Consequently, it is possible, for example, by adjusting the needle valves, to produce a dwell of four minutes of the work-carrying mechanism when the work is out of the liquid and a dwell of only two minutes when the work is in the liquid.

Referring again to Fig. 7, the follower 100 is provided with a port 130 and constitutes a valve for exhausting air from the lower end of the cylinder 106 after each starting operation produced by the piston 105. When the vertical bar 91 rises or falls to its median position the port 130 is shifted into alignment with a duct 131 in the bearing member 103 (see also Fig. 9). Then, the air below the piston 105 leaves the cylinder 106 (Fig. 6) through an exhaust pipe 132 and escapes through the duct 131 and the port 130. The bar 91 cannot open either of the supply valves 122 and 123 without closing the exhaust valve, and the latter cannot be open except when both supply valves are closed. The exhaust valve insures completion of the downward travel of the piston 105 before completion of every stroke of the plunger 65.

Referring to Figs. 3 and 14, the pump 110 supplies air also through a pipe 133, a portion of which is in the form of a coil and is located in the tank 20 below the heating units. Many small perforations are provided in the coil and are represented by dots in Fig. 14. These perforations emit small jets of air in the water 23 to amplify the output of vapor from the water. The air forced through the pipe 133 is obliged to flow through a valve 134 which is normally closed by the force of gravity and arranged to be opened by the pressure of air. This valve insures a sufficient pressure in the cylinder 106 to operate the piston 105 but enables all the available supply of air not delivered to the cylinder to escape in the water 23. Consequently, the soles in process of treatment will be subjected alternately to immersion in the water and to intermediate stages

of treatment with water vapor when the cage 21 is out of the water.

The motor 111 for driving the air pump is included in an electrical circuit 135 that also includes a mercury switch 136. This switch remains closed throughout a process of treatment, irrespective of the number of work-carrying cycles included in a course of treatment. In this respect, the duty of the switch 136 is like that of the primary switch 79 in the circuit that includes the motor 75. Accordingly, the switches 79 and 136 are both secured in a common holder 137 (Figs. 1, 5 and 10). This holder is affixed to a horizontal rockshaft 138 and is controlled manually to initiate a run of the apparatus but is operated by a counting unit 140 to open both of the circuits 78 and 135 at the conclusion of a predetermined number of work-treating cycles. Referring to Figs. 1 and 16 the casing of the counting unit 140 encloses a ratchet wheel of which a few of the ratchet teeth are indicated at 141. This ratchet wheel is located behind an adjustable dial 142 capable of being turned manually to any position according to the number of work-carrying cycles desired in a run of the apparatus. The ratchet wheel is advanced one tooth for each work-carrying cycle of the apparatus. A pawl (not shown) for operating the ratchet wheel receives its operating motion from upward movement of a rod 143. The lower end of this rod is connected to a rocker 144 mounted on a fulcrum pin 145 and provided with an arm that stands in the path of the vertically movable head 64. A spring 146 normally pulls down this arm of the rocker 144 to raise the rod 143 when the head 64 starts to descend from its highest position, but the operating pawl is shifted to another tooth of the ratchet wheel at the conclusion of each upward stroke of the head 64.

Assuming that the dial 142 has been adjusted to provide for four work-carrying cycles, the mechanism last described will advance the ratchet wheel three steps without producing any movement of the switches 79 and 136, but when the head 64 begins its next down stroke the ratchet mechanism will depress a rod 147 to stop both motors 75 and 111 while the work is still a considerable distance above the water 23. The lower end of the rod 147 is connected to an arm 148 affixed to the rockshaft 138 (see Figs. 5 and 10). Referring to Fig. 1, a torsion spring 149 is arranged to hold the arm 148 normally in a position to maintain the switches 79 and 136 in their closed positions (Figs. 10 and 13) but the force of this spring is inferior to that of the spring 146 which, at the conclusion of a run, furnishes the power for rocking the switches to their open positions.

The described control and operation of the switches 79 and 136 insures a stage of treatment with vapor after the final stage of immersion in the liquid but before operation of the air pump is stopped.

When the apparatus has been stopped as last described, an attendant may open the closure 21, remove the treated soles, replace them with untreated soles, return the closure to its closed position and initiate another course of treatment by depressing a trigger 150 (Fig. 16) that has a short range of travel in a slot 151 in the casing of the counting mechanism. This trigger retracts the operating pawl and a retaining pawl from the ratchet wheel which, upon being released, is returned to an initial position by a

spring, and thereby permits the torsion spring 148 (Fig. 1) to close the switches 78 and 136.

The wiring diagram represented in Fig. 13 includes feed wires 152 for supplying current to the circuits 44, 78, and 135. This figure also includes a double-pole switch 153 operable manually to connect the source of current with the three circuits described. Since the circuit 44 is automatically controlled by a thermo-regulator it is not necessary to disconnect this circuit from the source of current except when the apparatus is to be out of use for long periods of time. Under these circumstances, the manually operable switch 153 will serve to disconnect the circuit 44.

Having thus described my invention, what I claim as new and desire to secure by Letters Patent of the United States is:

1. An impregnating apparatus comprising a tank for holding a body of liquid impregnant, means for carrying work into and out of the liquid, a motor for operating said carrying means, means operable by said carrying means for stopping the motor, and timing means controlled by the carrying means for restarting the motor at the conclusion of a measured interval of dwell of the carrying means.

2. An impregnating apparatus comprising a tank for holding a body of liquid impregnant, means for carrying work into and out of the liquid, a motor for operating said carrying means, means operable by said carrying means for stopping the motor when the work is in the liquid and again when it is out of the liquid, timing means controlled by the carrying means, means controlled by the timing means for restarting the motor after an interval of dwell following each such interruption thereof, and adjustable means for regulating the timing means to determine the duration of the intervals of motor interruption.

3. An impregnating apparatus comprising a tank for holding a body of liquid impregnant, a motor, means operable by the motor for carrying the work into and out of the liquid repeatedly, manually operable means for starting the motor, means operable by the carrying means for stopping the motor at the conclusion of each cycle of carrying movement, and timing means controlled by the carrying means for restarting the motor after measuring the duration of the intervals of motor interruption.

4. An impregnating apparatus comprising a tank for holding a body of liquid impregnant, a motor, repeating means operable by the motor for carrying the work into and out of the liquid, counting means operable by the carrying means to count the carrying cycles thereof, means operable by the mounting means to stop the motor at the conclusion of a predetermined number of carrying cycles, means operable by the carrying means for interrupting the motor at intermediate stages in a run of the counting means, and timing means for restarting the motor after measuring the duration of the intervals of such motor interruption.

5. An impregnating apparatus comprising a tank for holding a body of liquid impregnant, a motor, repeating means operable by the motor for carrying the work into and out of the liquid, means operable by the carrying means for interrupting the motor twice in each carrying cycle, once while the work is in the liquid and once while out of the liquid, timing means for restarting the motor after measuring the duration of the intervals of such motor interruption, and

adjustable means for regulating the duration of alternate intervals without affecting the duration of the other intervals of motor interruption.

6. An impregnating apparatus comprising a tank for holding a body of liquid impregnant, an electrical circuit including a switch and a motor controlled thereby, means operable by the motor for carrying the work into and out of the liquid, means operable by the carrying means for opening the switch at a predetermined point in the carrying cycle, and timing means controlled by the carrying means for closing said switch after measuring the duration of an interval of motor interruption.

7. An impregnating apparatus comprising a tank for holding a body of liquid impregnant, an electrical circuit including a switch and a motor controlled thereby, means operable by the motor for carrying the work into and out of the liquid, repeating means operable by the carrying means twice in each carrying cycle for opening the switch, once when the work is in the liquid and once when out of the liquid, and timing means controlled by the carrying means for closing said switch after measuring the duration of each interval of motor interruption produced by said switch.

8. An apparatus as defined in claim 7 in which the electrical circuit also includes a primary starting switch in series with the switch first mentioned, and counting means operable by the carrying means for opening the primary starting switch at the conclusion of a predetermined number of carrying cycles.

9. An impregnating apparatus comprising a tank for holding a body of liquid impregnant, a work-supporting cage, power-operated mechanism for carrying the cage into and out of the liquid, and stationary means arranged to arrest downward travel of the cage at any one of a plurality of levels above the lowest level in the range of said carrying mechanism without arresting the latter.

10. An impregnating apparatus comprising means forming a treatment chamber and a replenishing chamber in communication with each other for holding a liquid impregnant in equilibrium, means including a ball cock in said replenishing chamber for supplying the latter with liquid to a minimum level, means movable down and up in said treatment chamber for carrying work into and out of the liquid, power-driven means for lowering and raising said carrying means, and adjustable means arranged to detain said carrying means at a variable level while said lowering and raising means continues through a portion of its cycle.

11. An impregnating apparatus comprising means forming a treatment chamber and a replenishing chamber in constant open communication with each other for holding a liquid impregnant in equilibrium, means including a ball cock in said replenishing chamber for supplying the latter with liquid to a minimum level, means movable down and up in said treatment chamber for carrying work into and out of the liquid, means for operating said carrying means, and means for emitting air under pressure in the liquid in said treatment chamber.

12. An impregnating apparatus comprising means forming a treatment chamber and a replenishing chamber in communication with each other for holding a liquid impregnant in equilibrium, means including a ball cock in said replenishing chamber for supplying the latter with liq-

uid to a minimum level, means movable down and up in said treatment chamber for carrying work into and out of the liquid, means for operating said carrying means, and adjustable means arranged to arrest and detain said carrying means at a minimum level without arresting said operating means.

13. An impregnating apparatus comprising means forming a closed treatment chamber, means for supplying warm water vapor to the upper part of said chamber while a body of water is maintained in the lower part thereof, means for carrying work into and out of the water in said chamber, a motor for operating said carrying means, means actuated by said carrying means to interrupt the motor when the work is out of the liquid, and timing means controlled by the carrying means for restarting the motor at the conclusion of a measured interval of motor interruption.

14. An impregnating apparatus comprising means forming a closed treatment chamber for enclosing a body of water and a vapor space above it, an electrical circuit including a motor, an air pump driven by said motor, an air conduit arranged to conduct air under pressure from said pump and emit it in said body of water, means for carrying work into and out of said body of water, an electrical circuit including a motor for operating said carrying means, means operable by said carrying means for counting the carrying cycles thereof, and means controlled by said counting means for opening both of said circuits at the conclusion of a predetermined number of carrying cycles.

15. An impregnating apparatus as defined in claim 14 in which the electrical circuit for co-operating with said carrying means includes an individual switch for interrupting the motor in that circuit, and timing means controlled by said carrying means for closing said individual switch after measuring the duration of the intervals of motor interruption.

16. An impregnating apparatus comprising means forming a closed treatment chamber for enclosing a body of water and a vapor space above it, an electrical circuit including a switch and a motor controlled thereby, means operable by said motor for carrying work into and out of the water in said chamber, means operable by said carrying means for opening said switch, pneumatic means for supplying air above atmospheric pressure in said body of water to produce bubbling thereof, timing means operable by air from said pneumatic means for closing said switch after measuring the duration of an interval of circuit interruption, and means operable by said carrying means for opening and closing communication between said pneumatic means and said timing means.

17. An impregnating apparatus comprising a tank for holding a body of liquid impregnant, an electrical circuit including a switch and a motor controlled thereby, means operable by said motor for carrying work into and out of the liquid in said tank, means operable by said carrying means for opening said switch, pneumatic timing means for closing said switch after measuring the duration of an interval of circuit interruption, a pump

5 for supplying air above atmospheric pressure to said timing means, another electrical circuit including an individual motor for driving said pump, means operable by said carrying means for opening and closing communication between said pump and said timing means, means operable by said carrying means for counting the carrying cycles thereof, and means operable by said counting means for opening both of said circuits.

10 18. An impregnating apparatus comprising a tank for holding a body of liquid impregnant, a vertical plunger extending through the bottom wall of the tank and having a bearing therein, work-supporting means arranged to be reciprocated vertically in the tank by said plunger, mechanism located under the tank for reciprocating the plunger, and adjustable means in the tank for arresting the downward travel of said work-supporting means at various points in its maximum range afforded by said mechanism.

15 19. An impregnating apparatus comprising a tank for holding a body of liquid impregnant, a vertical plunger extending through the bottom wall of said tank and having a bearing therein, work-supporting means arranged to be reciprocated vertically in the tank by said plunger, two cooperative cranks of equal throw arranged below said tank, means for driving said cranks in synchronism but in opposite directions, and a crosshead secured to said plunger and engaging said cranks to be carried up and down thereby.

20 20. An impregnating apparatus comprising a tank for holding a body of liquid impregnant, a work carrier movable up and down in the tank, power-driven mechanism by which said carrier is successively reciprocated and detained in a predetermined elevated position in the tank, power-operated means by which said mechanism is periodically stopped when said carrier is in said elevated position, and timing means by which said mechanism is restarted after an interval of predetermined duration.

25 21. An impregnating apparatus comprising a tank for holding a body of liquid impregnant, a work carrier movable up and down in the tank, power-driven mechanism by which said carrier is reciprocated and detained alternately in a predetermined elevated position and a predetermined lower position through individual periods of dwell, means operable by said mechanism for stopping the latter when said carrier is in either of the two positions specified, and timing means by which said mechanism is restarted in each of its stopping positions after an interval of predetermined duration.

30 22. An impregnating apparatus comprising a tank for holding a body of liquid impregnant, a work carrier, a crank by which the work carrier is moved up and down in the tank, an electrical circuit including a motor, transmission means driven by the motor for rotating the crank, means operable by the crank for opening said circuit twice in each cycle thereof, timing means controlled by the crank for measuring the duration of each interval of circuit interruption, and means controlled by the timing means for closing the circuit.
